G. WESSELL

EGG BEATER

Original Filed Aug. 18, 1921

Inventor
George Wessell,
By his Attorneys

Edgar Hale Co.

UNITED STATES PATENT OFFICE.

GEORGE WESSELL, OF BROOKLYN, NEW YORK.

EGG BEATER.

Application filed August 18, 1921, Serial No. 493,382. Renewed May 8, 1924.

To all whom it may concern:

Be it known that I, GEORGE WESSELL, a citizen of the United States, and residing at Brooklyn, in the county of Kings and State of New York, have invented certain new and useful Improvements in Egg Beaters, of which the following is a specification, such as will enable those skilled in the art to which it appertains to make and use the same.

This invention relates to what are known as egg beaters, and the object thereof is to provide an improved device of this class which may be used for the purpose specified and for the purpose of beating up, or beating up and mingling other liquid or partially liquid or soft substances; a further object being to provide a device of the class specified which is simple in construction, 20 efficient in use and comparatively inexpensive, and which will operate freely and smoothly and without the jolting, jarring or locking of other devices of this class as sometimes constructed; and with these and other objects in view the invention consists in a device of the class specified, constructed and operated as hereinafter described and claimed.

The invention is fully disclosed in the following specification, of which the accompanying drawing forms a part, in which the separate parts of my improvement are designated by suitable reference characters in each of the views, and in which:—

Fig. 1 is a side view of my improved beater partially in vertical section;

Fig. 2 a side view of part of my improved beater looking in the direction of the arrow 2 of Fig. 1;

Fig. 3 a sectional view on the line 3—3 of Fig. 1; and,

Fig. 4 a detail view of a main drive wheel which I employ and showing parts of two gear wheels or sprocket wheels which operate in connection therewith.

In the practice of my invention, or in reducing the same to practical form, I employ a main bottom frame member *a*, which is made from strong heavy wire and is approximately yoke-shaped or U-shaped in form, and is open at the top and closed at the bottom thus forming two side bottom frame members *a*² on which the blade members *b* are mounted in the usual manner, and the general form of the bottom frame member *a* and the blade members *b* is old

and well known and independent of the details of construction, hereinafter described, form no part of my invention.

The blade members *b* are composed of 60 separate vertically arranged parts *b*² of the usual form, the tops of which are bent inwardly and overlap, and the side members *a*² of the bottom frame member *a* are passed upwardly and through the overlapped top 65 parts of the side bottom frame members *a*², as clearly shown at *c*, and mounted on and secured to the tops of the blades *b* are gear or sprocket wheels *c*² which together with the blades *b* are rotatable on 70 the top parts of the side bottom frame members *a*², and said bottom frame members *a*² above the gear or sprocket wheels *c*² are bent inwardly as shown at *a*³ and provided with upwardly directed eye members *a*⁴.

I also provide a reinforcing member *d* which is yoke-shaped in form, and the side portions of which are provided with offset 80 bearings or anchoring portions *d*² which partially surround or enclose the inwardly and upwardly directed parts *a*³ and *a*⁴ of the bottom side frame members *a*² above the gear or sprocket wheels *c*² and below the eye members *a*⁴. I also provide a main 85 top frame member *e* which is preferably formed from heavy sheet metal, the bottom portion of which consists of two parallel side members *e*² between which is mounted a main gear or drive wheel *f*. The main 90 gear wheel *f* is provided with a central tubular hub *f*² and the side parts *e*² of the top frame member *e* are provided with circular apertures *e*³ having inwardly directed sleeve bearing members *e*⁴, and I also provide a crank device *g* by which the gear 95 wheel *f* is operated, and said crank device is provided with an arm *g*² and a handle arm *g*³ on which a handle *g*⁴ is mounted, and the arm *g*² of the crank *g* is provided 100 with a reduced portion *g*⁵ which is passed through the hub *f*² of the wheel *f* and secured therein or thereto.

The side members *e*² of the top frame member *e* are carried or extended downwardly and are divided to form separate parts *e*⁵ which are folded upwardly, inwardly and downwardly around the offset bearings or anchoring portions *d*² of the part *d*, and in the construction shown, rivets *j* are passed through the eyes *a*⁴ and riveted 110 in the side parts *e*² of the main top frame

members e and this construction including the part d , the lower end portions of the side members e^2 of the main top frame e and the top parts of the bottom of the 5 side portions a^2 of the main bottom frame member a securely binds the main and bottom and top frame members together and holds these separate parts of the device in proper position and prevents loose or 10 vibratory movement thereof in the operation of the beater.

The main gear or drive wheel f is composed of sheet metal and the outer edge portion thereof is provided with radially 15 arranged teeth f^3 on both sides thereof and corresponding and alternating radial grooves f^4 formed in or in connection with said wheel by stamping or other processes, and said wheel extends downwardly be- 20 tween the sprockets or gears c^2 and the teeth of said gears or sprockets engage with the teeth f^3 on the opposite sides of the gear wheel f as is clearly shown, and will be readily understood, and by turn- 25 ing the crank g the blade members b will be rotated as will also be readily understood.

The teeth f^3 and grooves f^4 with which the gear wheel f is provided are elongated 30 radially, and said teeth and grooves gradually diminish inwardly in transverse section, and the teeth of the gears or sprockets c^2 are rounded to correspond with the side curves of the teeth f^3 and grooves f^4 of the 35 wheel f , and this insures a smooth and continuous operation of the blades b without any jolt or jar thereof, or interlocking of the gears or sprockets c^2 and the main gear wheel f , and the construction herein shown 40 and described also prevents any vertical movement of the blade members b , which movement is a great objection to some of the devices of this class, as now constructed, as it causes an interference or locking move- 45 ment between the gears or sprockets c^2 and the main drive wheel in such devices.

With my improvement the side portions e^2 of the main top frame member e are bent inwardly above the drive wheel f and secured together in any desired manner to form a shank portion e^6 , the side portions of 50 which are separated at e^7 and bent outwardly and inwardly to form folded arms or handle supports e^8 which are counter- 55 sunk in the bottom of a handle member h , and secured thereto by rivets, bolts or other devices h^2 .

It will be understood that the main drive 60 wheel f operates between the side portions of the reinforcing yoke-shaped device d , and the operation of my improved beater will be the same as that of others of its class, and while I have shown and described cer- 65 tain details of construction which I em- 70 ploy, my invention is not limited to such

details, and various changes therein and modifications thereof may be made, within the scope of the appended claims, without departing from the spirit of my invention or sacrificing its advantages. 75

Having fully described my invention, what I claim as new and desire to secure by Letters Patent, is:—

1. A beater of the class described comprising a framework composed of separate top and bottom frame members secured together approximately centrally thereof, beater blades rotatably mounted upon the bottom member of the framework, a drive wheel rotatably mounted in connection with the top member of the framework and in operative connection with said beater blades, the upper ends of the bottom member being bent inwardly and upwardly and the lower ends of the top member being fashioned to receive the upper ends of the bottom member, and a reinforcing yoke-shaped member mounted in keepers at the lower ends of said top member and engaging the inwardly and upwardly bent ends of the bottom member for securing said frame members together. 80

2. A beater of the class described comprising a framework composed of separate top and bottom frame members secured together approximately centrally thereof, beater blades rotatably mounted upon the bottom member of the framework, a drive wheel rotatably mounted in connection with the top member of the framework and in operative connection with said beater blades, the upper ends of the bottom member being bent inwardly and upwardly and the lower ends of the top member being fashioned to receive the upper ends of the bottom member, a reinforcing yoke-shaped member mounted in keepers at the lower ends of said top member and engaging the inwardly and upwardly bent ends of the bottom member for securing said frame members together, the ends of said bottom frame member being provided above said yoke-shaped member with eyes, and means passed through said eyes for securing the same to said top frame member. 90

3. A beater of the class described comprising a framework composed of separate top and bottom frame members secured together approximately centrally thereof, beater blades rotatably mounted upon the bottom member of the framework, a drive wheel rotatably mounted in connection with the top member of the framework and in operative connection with said beater blades, the upper ends of the bottom member being bent inwardly and upwardly and the lower ends of the top member being fashioned to receive the upper ends of the bottom member, a reinforcing yoke-shaped member mounted in keepers at the lower ends of said top 100

member and engaging the inwardly and upwardly bent ends of the bottom member for securing said frame members together, the ends of said bottom frame member being provided above said yoke-shaped member with eyes, means passed through said eyes for securing the same to said top frame member, and a wooden handle member secured to the upper end of said top frame member.

4. A frame construction for beaters of the class described comprising top and bottom frame members, the top frame member being composed of strip sheet metal and the lower end of which is approximately yoke-shaped in form, the bottom frame member being composed of rod-like material and being yoke-shaped in form, the upper ends of said bottom frame member being bent inwardly and upwardly, the lower ends of said top frame member being provided with keepers, means passed through said keepers for holding said frame members together and for reinforcing the same where joined.

5. A frame construction for beaters of the

class described comprising top and bottom frame members, the top frame member being composed of strip sheet metal and the lower end of which is approximately yoke-shaped in form, the bottom frame member being composed of rod-like material and being yoke-shaped in form, the upper ends of said bottom frame member being bent inwardly and upwardly, the lower ends of said top frame member being provided with keepers, means passed through said keepers for holding said frame members together and for reinforcing the same where joined, the ends of said bottom frame member being provided above said means with eyes, and means passed through said eyes for securing the same to said top frame member.

In testimony that I claim the foregoing as my invention I have signed my name in presence of the subscribing witnesses this 16th day of August, 1921.

GEORGE WESSELL.
